UNITED STATES PATENT OFFICE.

ADELMER M. BATES, OF CHICAGO, ILLINOIS, ASSIGNOR, BY MESNE ASSIGNMENTS, TO
BATES VALVE BAG CORPORATION, OF CHICAGO, ILLINOIS, A CORPORATION OF
DELAWARE.

PROCESS OF MAKING AND FILLING BAGS.

Application filed April 23, 1923. Serial No. 633,904.

My invention relates to a method of producing filled bags, and more particularly relates to a modification of the processes disclosed in my prior Patents No. 693,820, granted February 18, 1902, and No. 1,143,801, granted June 22, 1915.

The principal object of my invention is to provide filled bags with the use of a minimum amount of bag forming material.

10 Another object is to reduce to a minimum the amount of bag forming material which must be kept on hand in preparation for the production of bags containing various weights of filling material.

15 Another object of my invention is to mark the bag material in such a manner that the filled bags produced therefrom will be properly marked without interfering with the economical use of the material.

20 The principal difficulties the invention is intended to overcome arise in the following manner:

The commercial demand is for bags containing charges of uniform weight, and accordingly the size of the charge is determined by weight, not by bulk. The materials customarily bagged do not run of even density or specific gravity throughout, with the consequence that uniform weights of a 25 given material have varying bulks. For example, a five pound charge of comparatively dense salt is less bulky than an equal weight of comparatively loose salt, so that different five pound charges of salt will be of different bulk. The bulkiest charge encountered will be materially more bulky than the average charge, and the average charge materially more bulky than the least bulky charge. It is obvious that all bags completely made up 30

40 in advance of filling must be large enough to contain the bulkiest charge, otherwise some of the packages will be underweight. The necessary result is that the bags are made materially larger than is needed to contain the average charge.

Where the charge is filled into the tube and then the filled end of the tube is closed and severed to form a filled bag, as in the patents mentioned above, and the closing means and the support for the filled end have a fixed relation, or a relation not dependent upon the bulk of the individual charge being dealt 50

with, the relation must be such that each bag will be long enough to enclose the bulkiest charge. The result is the same as where the individual bags are made up in advance of filling, that is, the bags are materially larger than are required for the average charge. It is customary to print brands at uniform intervals upon the strips of material from which bags are to be formed, and this has furnished an added incentive to make the bags of uniform size, so that the brands will be properly placed on the finished bags.

In carrying out both of the above processes, each bag must be large enough to contain the bulkiest charge, and the practice has been to form them uniformly of that required size, thus requiring a considerable amount of bag making material in excess of that which would be needed to make each bag just large enough to contain the particular charge which is actually filled into it, which loss is obviated by my invention.

Another element of saving that results 75 from my invention is due to the fact that the width of the material from which bags are made does not run uniform. For example, a length of bag cloth, as it comes from the loom, is from one to two inches wider at its widest point than it is at its narrowest point, and under the practice of making all bags of uniform length, the narrowest must be wide enough to contain the bulkiest charge, and there is no use in any bag being wider than the narrowest. For this reason it is customary to trim the cloth to uniform width before making bags therefrom, and a considerable amount of material, including the strong selvage edge, is cut away by the trimming.

Many materials are sold in bags having a fixed price, the weight of a charge in a package, instead of the price of the package, varying with the market. For example, table salt is sold largely in five cent bags and ten cent bags. For a time, conditions may demand filling five pound salt bags for the ten cent trade. Obviously, a sufficient supply of five pound bags or bag material must be prepared to meet this demand. But a sudden change in the market may cause an immediate demand for four, four and one-half, five and one-half, or six pound bags,

and preparation must be made to meet this demand, should it occur. The consequence is that much money and storage space is tied up in bags and bag material prepared to meet possible demands, and even then suddenly changed demands cannot be fully anticipated.

By my method each bag is made just large enough to contain the individual charge 10 which is actually filled into it, there is no wasteful trimming, and the amount of bag material that must be prepared to meet varying demands is reduced to a minimum.

Other features of the invention will appear as the description proceeds.

Referring to the accompanying drawing, which forms a part of this specification:

Fig. 1 diagrammatically illustrates my bag filling and closing process.

Fig. 2 shows a portion of a length of printed bag forming material.

Figs. 3, 4 and 5 show three of the bags produced by my process.

According to my process, an end of bag tubing 1 is drawn from a filling tube 2, preferably over a spreading member 3 and under a retaining member 4. The drawn-off end is closed, and then a charge of filling material is fed through the feeding tube into the 30 closed end of the bag tube. After the charge has been suitably compacted, the walls of the bag tube are brought together immediately above the charge, two closures are made, as by sewing seams at the points indicated by dotted lines 5 and 6 on Fig. 1, and the tube is severed between the closures, as along the line 7, thus completing the filled bag.

The closures are made as closely as practicable to the upper end of the charge, the charge being the guide, and no attention is paid to the distance between the closed end and the point being closed, nor to the location of any mark which the tubes may have 45 thereon. In this way the bag tubing is utilized without any waste, each bag being formed of as short a length of tubing as will contain the particular charge filled thereinto.

In making bag tubing for use in such a 50 filling method, it is feasible to utilize all of a length of material, without trimming. A length of material 8 with irregular selvage edges 9, 10, as shown in Fig. 2, may have these irregular edges united to form one 55 tube, or the strip may be cut lengthwise, as at 11, and each selvage edge united to a cut edge to form two tubes, or the length may be cut into more than two strips, as by cutting along dotted lines indicated at 12. In

any case, there is no need of trimming, and the full width of each strip is utilized, the tube being made of as large diameter at each point as the width of the strip at that point will allow. In this way the waste due to 10 trimming is avoided, and the strength of the

selvage edges is retained in the seams. The result will be filled bags of different lengths and widths, as illustrated in Figs. 3, 4 and 5, but none of the bag making material is wasted.

It is usually desirable to have some form of marking on the finished bags. It is obvious that the desired marks may be placed upon the bags in any suitable manner after they are filled, or it would be possible to place all desired marks upon them as a part of the filling process, the marks being placed upon the bag tube as it is fed to the filling point. However, I prefer to print the brands on the length of bag material in an all-over design, such as indicated by 13, Fig. 2, the size and relation of the marks being such that at least one complete mark will appear upon each bag, no matter how the material is cut to form the bag. In this way the bags are properly marked without any attention to the location of the marks during the filling, closing and severing process.

All desired markings may be included in this all-over design where only one weight of charge is to be filled into any bag to be made from a given length: but where the demand fluctuates as to the weight of the charge, the weight mark may be omitted from the all-over design, and only those marks included which indicate origin, material, or other matter which does not change with changing weights of charges. Then the same tube may be used with quite a variation in weights of charges, and a still greater variation of charges may be provided for without any change in the printed material, by varying the number of strips into which a tube is cut.

My invention is in part applicable to the manufacture of unfilled bags inasmuch as the size and location of the brand marks make it possible to utilize a single strip of bag fabric or bag tubing to manufacture bags of various sizes, each one containing properly located brand marks.

If it is desired to have a single brand mark on each package, it may be applied to the space 14 between the bottom of the filling tube and the sewing mechanism, or the printing mechanism may be located so as to print the marks immediately before the tube is formed in the type of apparatus illustrated in Fig. 1, and in either case the printing will be done only a few bag lengths from the closed end of the tube and the brand marks so located as to come approximately in the center of a side of the filled package.

Where the same all-over design is used on bags containing different weights, the weight 125 may be impressed subsequently, and I prefer to do it as a part of the bag filling, closing and severing process. As the weight mark is liable to partially overlap some portion of the all-over design, I prefer to make 130

the weight mark of a different color from the all-over design, so that it may be clearly seen in spite of such partial overlapping.

When desired, each alternate mark of the all-over design may be reversed, so that it may be read from either end of the bag, and other changes may be made within the scope of the appended claims.

I claim:

1. The method of making filled bags, which consists in marking bag fabric with a series of marks so placed and of such size that the smallest contemplated bag will show at least one complete mark, however 15 the material is cut to form such bag, forming a tube from the marked fabric, filling successive properly weighed charges into the tube, closing the tube adjacent each successive charge, the charge being the guide, and 20 severing the tube adjacent each closure.

2. The method of making filled bags, which consists in marking bag fabric with a series of marks so placed and of such size that the smallest contemplated bag will show 25 at least one complete mark, however the material is cut to form such bag, forming the fabric into strips of such width that the entire fabric is utilized without trimming, forming a tube from a strip, filling successive properly weighed charges into the tube, closing the tube adjacent each successive charge, the charge being the guide, and severing the tube adjacent each closure.

3. The method of making filled bags, which consists in marking bag fabric with 35 a series of marks so placed and of such size that the smallest contemplated bag will show at least one complete mark, however the material is cut to form such bag, forming the fabric into strips of such width that the entire fabric is utilized without trimming, forming a strip into a tube having at 40 each point the maximum diameter the width of the strip at that point will warrant, filling successive properly weighed charges into the tube, closing the tube adjacent each successive charge, the charge being the guide, and severing the tube adjacent each closure.

4. The method of making filled bags, which consists in marking bag fabric with 50 a series of marks which do not need to be varied for bags containing different weights of material, the marks being so placed and of such size that the smallest contemplated bag will show at least one complete mark, however the material is cut to form such bag, forming a tube from the marked fabric, filling successive properly weighted charges 55 into the tube, closing the tube adjacent each successive charge, the charge being the guide, severing the tube adjacent each closure, and marking the weight on each bag as a part of the bag forming and filling operation.

5. The method of making filled bags,

which consists in marking bag fabric with a series of marks which do not need to be varied for bags containing different weights of material, the marks being so placed and of such size that the smallest contemplated bag will show at least one complete mark, however the material is cut to form such bag, and each alternate mark being reversed, forming the fabric into strips of such width that the entire fabric is utilized without 75 trimming, forming the strips into tubes having at each point the maximum diameter the width of the strip at that point will warrant, filling successive properly weighed charges into each tube, and closing each tube 80 adjacent each successive charge, the charge being the guide, severing adjacent each closure, and marking the weight on each bag as a part of the bag forming and filling operation.

6. The method of making filled bags, which consists in marking bag fabric with a series of marks which do not need to be varied for bags containing different weights of material, the marks being so placed and of such size that the smallest contemplated bag will show at least one complete mark, however the material is cut to form such bag, forming a tube from the marked fabric, filling successive properly weighed charges 90 into the tube, closing the tube adjacent each successive charge, the charge being the guide, severing the tube adjacent each closure, and marking the weight on each bag as a part of the bag forming and filling operation, 95

the weight mark being made of a different color from the previously formed marks.

7. The method of making filled bags, which consists in marking bag fabric with 100 a series of marks which do not need to be varied for bags containing different weights of material, the marks being so placed and of such size that the smallest contemplated bag will show at least one perfect mark, however the material is cut to form such bag, and each alternate mark being reversed, forming the fabric into strips of such width that the entire fabric is utilized without 105 trimming, forming the strips into tubes having at each point the maximum diameter the width of the strip at that point will warrant, filling successive properly weighed charges into each tube, and closing each tube 110 adjacent each successive charge, the charge being the guide, severing adjacent each closure, and marking the weight on each bag as a part of the bag forming and filling operation, the weight mark being made of a different color from the previously formed marks.
